[57] CLAIM

The ornamental design for a tripod lantern support, as shown and described.

DESCRIPTION

FIG. 1 is a front perspective view of a tripod lantern support showing my new design;

FIG. 2 is a frontal perspective view thereof, with the tripod lantern support illustrated disposed in a portable position;

FIG. 3 is an enlarged, fragmentary elevational view showing the internal hook support;

FIG. 4 is an enlarged, fragmentary perspective view showing the top portion of a leg of my new design;

FIG. 5 is an enlarged, fragmentary perspective view showing the bottom portion of a leg;

FIG. 6 is an enlarged, fragmentary, bottom perspective view thereof;

FIG. 7 is a greatly enlarged fragmentary top perspective view thereof;

FIG. 8 is an upper rear perspective view, as viewed generally from a position to the rear of FIG. 1;

FIG. 9 is a bottom perspective view with the legs in an extended position;

FIG. 10 is an enlarged fragmentary sectional view of a portion of one of the telescoping legs.
